UNITED STATES PATENT OFFICE

JOHN KOVATS, OF BRIDGEPORT, CONNECTICUT

FOLDING TABLE

Application filed June 6, 1929. Serial No. 368,814.

This invention relates to a table, particularly the means for mounting the supporting legs of the table, and has for an object to provide means for so connecting the supporting legs to the table that they may all be folded against the under side of the table and are connected by mechanism so that the swinging of any leg to or from the extended or supporting position will impart a similar movement to each of the other legs.

It is also an object of the invention to provide a construction in which there is an individual locking means for each leg which is so connected with the locking means for each of the other legs that operation of any one to lock or unlock the leg will automatically operate each and all of the other locking means in the same manner, so that the release of any one locking means will release all the other locking means to permit the legs to be swung to folded position, and the locking of any one leg in the extended position will also lock each of the other legs in this position.

It is another object of the invention to provide a construction in which, although all the legs may be swung to or from the extended or folded position by swinging any individual leg on its pivot, still the legs are rigidly held in the supporting position to provide a rigid support for the table.

Still another object of the invention is to provide a construction of this character in which practically the entire structure may be stamped from sheet metal and may be manufactured and assembled at relatively low cost.

With the foregoing and other objects in view the invention consists in certain novel features of construction, combinations and arrangements of parts as will be more fully disclosed in connection with the accompanying drawing.

In this drawing

Fig. 1 is a bottom plan view of the table showing the legs folded against the under side thereof.

Fig. 2 is a partial section of the table showing the mounting means for one leg in elevation and with the parts in the position they occupy when the leg is in the upright or supporting position.

Fig. 3 is a partial longitudinal section and partial plan view of the mounting means for one leg, the parts being in the position of Fig. 2.

Fig. 4 is a detail section substantially on line 4—4 of Fig. 2, and on an enlarged scale.

Fig. 5 is a detail section substantially on line 5—5 of Fig. 2 and on an enlarged scale.

Fig. 6 is a detail of an adjustable coupling for the cable.

Figs. 7 and 8 are front and side elevations respectively of the pivoted member for mounting the leg.

Fig. 9 is a detail of the construction of the mounting bracket.

Fig. 10 is a detail of the guide member, and

Fig. 11 is a detail section of one of the guide pulleys.

This device is adapted for tables of various types but is especially intended for use on what are commonly known as card tables in which the legs are foldable against the under side of the table top, so that the table may be folded into a small space and put away into a closet or other suitable space when not in use, and the device is, therefore, shown in the drawings as applied to this type of table. The table top is shown at 12 which, of course, may be of any suitable material and may be finished on the top or covered with any suitable cover as is found desirable. Secured to the under side of this top of the table and extending about the periphery thereof are usually mounted wooden bars 13 which strengthen and stiffen the table top and assist in preventing warping. The table shown is a substantially square or rectangular table and is, therefore, provided with a supporting leg 14 at each corner. These legs are each pivoted to the table so as to fold or swing against the under side thereof and they are all mounted in the same manner. They thus each swing in the same direction in relation to the periphery of the table from their individual corners and lie substantially parallel with the bar or flange 13 when they are folded against the under side of the table top. As the means for mounting each is the same as that for mounting each of the other legs one set of dies may be used for making all the mount-

ings and they are, therefore, each interchangeable, and I will describe but one of them.

The legs 14 are shown as substantially square in cross section, but of course, may be of any shape desired. The upper end of each is secured in a holder 15 which is preferably made of sheet metal, and this is of substantially U-shape in cross section to receive the upper end of the leg, and therefore, embraces it on three sides, and it may be secured thereto by any suitable means such as screws or bolts 16. This member is provided with ears 17 and 18 preferably spaced laterally from the sides of the member as indicated in Figs. 3 and 7 so as to give lateral strength and stiffness to properly brace the leg when these ears are pivoted to the supporting bracket 19. The ears 17 and 18 are integral with the sides of the member 15 by the connecting strips 20 and 21 respectively. The bracket 19 is also preferably of sheet metal and is bent to substantially U-shape to provide ears 22 and 23 to which the ears 17 and 18 are pivoted respectively by the rivets 24. These ears 22 and 23 have extensions 25 on their edges passing through openings in a plate 26 and riveted over to secure them to this plate as shown in Fig. 9. The plate 26 may be secured to the bars 13 by screws 27.

It will be noted from Fig. 1 that when securing the brackets 19 to the under side of the table they are so arranged that the legs all fold in the same direction peripherally of the table. Also that the spaced relation of pivot ears 17 and 18 make a very rigid support for the leg in a direction transverse of the direction of its swinging movement, that is the up and down directions as viewed in Fig. 3.

Also preferably secured to these brackets 19 and secured on the inner sides of the bars 13 adjacent each leg by any suitable means such as screws 28 is a guide plate or bar 29. This plate or bar may also be made of sheet metal and has a laterally pressed longitudinally extending rib portion 30 in which is provided a guide slot 31. At the end adjacent the leg this slot has a downwardly extending portion 32 running into an upward extending portion 33 at this end of the slot. Mounted to slide along the bar 29 is a block 34 which may be a simple flat piece of metal and it carries shouldered rivets 35 extending through the slot 31 and having a head 36 running in the groove formed at the back of the rib 30. These rivets guide the block 34 for longitudinal movement along the bar 29. The blocks 34 also carry clamps 37 which are secured thereto by any suitable means such as screws 38. This clamp is folded over to form a grooved portion 39 to embrace a flexible cable 40 and clamp this cable to the block 34 through the clamping effect of the screws 38.

To one of the rivets 35 there is pivoted a link 41, and at its other end it is pivoted by means of a similar rivet 42 to a brace link 43 which brace link is pivoted at its opposite end to the member 15 or the leg at the point 44. The rivet 42 is also a shouldered rivet and is guided for longitudinal movement in the slot 31.

The flexible cable 40 may be of any suitable material, but it is preferably of stranded wire, and extends entirely around the table inside of the side bars 13 and at each corner it runs over a flanged guide pulley 45. This pulley may also be made of sheet metal as shown in Fig. 11. The free ends of the cable are connected together by an adjustable connection of any suitable construction. A very simple type of connection is shown in Fig. 6 in which elements 46 are secured to the free ends of the cable and have overlapping portions 47 provided with a series of openings 48 through which may be passed a securing screw 49. By overlapping these portions more or less and inserting the screw, the cable may be tightened or loosened as desired.

Operation.—It will be apparent from the foregoing description that when a leg is swung about its pivots 24 the link brace 43 will cause the block 34 to slide along the guide bar 29, and as the block 34 for each leg is clamped to the cable 40 any movement of any block 34 will be transmitted to the cable and by the cable will be transmitted to each of the other blocks 34 for the remaining three legs. Thus, if any one leg 14 is swung from its folded position of Fig. 1 at the under side of the table to the upright or extended position of Figs. 2 and 3 its block 34 will slide along the bar 29 from the position adjacent its outer end (the right end as viewed in Figs. 2 and 3) toward the leg or to the left as viewed in Figs. 2 and 3. During this movement the rivet 42 which is the pivotal connection between the links 41 and 43 will be guided along the guide slot 31 and when the leg reaches nearly its upright position, as indicated in dotted lines of Fig. 2, this rivet 42 will pass into the inclined portion 32 of this slot 31 and into a position in alignment with the inclined portion 33 of this slot. Then if the operator presses inwardly on the inner edge 43' of the link 43, especially adjacent the rivet 42, he will force this rivet into the inclined portion 33 of the slot to the full line position of Fig. 2. As this portion 33 of the slot extends substantially at right angles to the link 43 it will be obvious that pressure on the outside of the leg tending to fold it against the table will be prevented from doing so by the link 43 and engagement of the rivet 42 against the side portion 33 of the slot. Thus, the leg is locked in its upright or table supporting position and is very firmly held in this position by the brace

link 43. It is preferred that the portion 33 of the slot be formed on the arc of a circle with the center of the pivot 44 as its center. This will give a very reliable locking effect. 5 It is to be especially noted that when the operator presses on the link 43 to force the rivet 42 from the inclined portion 32 of the slot into the portion 33 the block 34 is shifted somewhat, and that therefore, a similar 10 movement is imparted by the cable 40 to the block 34 of each of the other legs, and this movement of each of these blocks acting through their links 41 force the rivet 42 of each of these legs into the inclined portion 33 15 of its guide slot. Thus, the locking of any one leg will lock each of all the other legs at the same time.

In collapsing the legs and folding them against the under side of the table this operation is simply reversed, that is, the operator by pressing the inner side 50 of any link 43 will slide the rivet 42 upwardly in the inclined portion 33 of the slot and bring it into alignment with the portion 32 of the slot. 20 This unlocks that particular leg and at the same time also unlocks each of the other legs through the movement of the blocks 34 and the cable 40. The operator may now fold any individual leg against the under side of 25 the table, and this operation will fold each and all of the other legs against the under side of the table at the same time. Thus, with this construction the swinging of any one leg toward or from either its upright or 30 folded position will automatically impart a similar movement to each of the other legs, and the locking or unlocking of any individual leg by swinging the free end of the link 43 will lock or unlock each of the other legs in a similar manner.

Having thus set forth the nature of my invention, what I claim is:

1. In a table, a plurality of supporting legs pivoted to the table on individual pivots arranged so that all the legs fold in the same direction with respect to the periphery of the table, guides at the corners of the table, a flexible cable running over these guides, a guide bar secured to the table adjacent each leg and provided with a guide way having an offset portion, movable blocks having guide means in said guide ways, there being a block for each leg, means for securing the blocks to the cable, a brace link pivoted to each leg, 45 and a connecting link pivoted to each brace and to the adjacent block, the pivotal connection between the two links being guided in said guide way.

2. In a table, a plurality of supporting legs pivoted to the table and foldable against it, means for connecting the legs with each other so that movement of any leg will give similar movement to the other legs including a flexible cable and a movable block adjacent each leg secured to said cable, a guide means

for each block, a connection from each leg to a block, and cooperating locking means on the guide means and said connection to lock the leg in extended or supporting position.

3. In a table, a plurality of supporting legs pivoted to the table and foldable against it, means for connecting the legs with each other so that movement of any leg will give similar movement to the other legs including a flexible cable and a movable block adjacent each leg secured to said cable, a guide member secured to the table adjacent each block provided with a longitudinal slot having an offset portion at its end toward the leg, means on the block guided in said slot, a brace link pivoted to the leg, a connecting link pivoted to the block, and a pivotal connection between the two links guided in said slot. 70

4. In a table, a plurality of supporting legs pivoted to the table and foldable against it, means for connecting the legs with each other so that movement of any leg will give similar movement to the other legs including a movable block adjacent each leg and connecting means between the blocks, a guide member secured to the table adjacent each block and provided with a longitudinal slot having an offset portion at its end toward the leg, means on the block guided in said slot, a brace link pivoted to the leg, a connecting link pivoted to the block, and a pivotal connection between the links guided in said slot. 85

5. In a table, a plurality of supporting legs pivoted to the table and foldable against it, means for connecting the legs with each other so that movement of any leg will give similar movement to the other legs including a movable block adjacent each leg and connecting means between the blocks, a guide member secured to the table adjacent each block and provided with a longitudinal slot having an offset portion at its end toward the leg, means on the block guided in said slot, a brace link pivoted to the leg, a connecting link pivoted to the block, and a pivotal connection between the links guided in said slot, 90

said offset portion of the slot being at substantially right angles to the brace link when the leg is in supporting position and connected to the main portion of the slot by a portion which is inclined to both the main and offset portions of the slot. 100

6. In a table, a plurality of supporting legs pivoted to the table and foldable against it, means for connecting the legs with each other so that movement of any leg will give similar movement to the other legs including a flexible cable and a movable block adjacent each leg secured to said cable, a guide member secured to the table adjacent each block provided with a longitudinal slot having an offset portion at its end toward the leg, means on the block guided in said slot, a brace link pivoted to the leg, a connecting link pivoted to the block, and a pivotal connection be- 110

tween the two links guided in said slot, said offset portion of the slot being at substantially right angles to the brace link when the leg is in supporting position and connected to the main portion of the slot by a portion which is inclined to this main portion.

7. In a substantially rectangular table, a supporting leg pivoted thereto adjacent each corner and adapted to fold against the table, 10 a roller guide mounted adjacent each corner, a flexible cable passing over said guides, a guide member secured to the table adjacent each leg and having a guide slot offset at one end at an angle to the main slot and connected therewith by an inclined portion, a clamp secured to the cable adjacent each guide member, a guide on each clamp running in the corresponding slot, a brace link pivoted to each leg, a guide means connected to each 15 brace link running in the adjacent slot and adapted to enter said offset portion thereof to lock the leg in supporting position, and a connection between the clamp and the brace link.

8. In a table, a plurality of supporting legs 20 pivoted to the table and foldable against it, means for connecting the legs with each other so that movement of any leg will give similar movement to the other legs including a movable block adjacent each leg and 25 connecting means between the blocks, a guide member secured to the table adjacent each leg and having a guide slot offset at one end at an angle to the main slot and connected therewith by an inclined portion, a guide 30 means connected to each brace link running in the adjacent slot and adapted to enter said offset portion thereof to lock the leg in supporting position, and a connection between 35 each block and the adjacent brace link.

40 In testimony whereof I affix my signature.
JOHN KOVATS.
